UNITED STATES PATENT OFFICE

LOUIS SCHWITZER, OF INDIANAPOLIS, INDIANA, ASSIGNOR TO SCHWITZER & HALTENBERGER, OF INDIANAPOLIS, INDIANA, A COPARTNERSHIP COMPOSED OF LOUIS SCHWITZER AND JULES HALTENBERGER.

STARTER FOR INTERNAL-COMBUSTION ENGINES.

1,069,818.

Specification of Letters Patent. Patented Aug. 12, 1913.

Application filed November 27, 1911. Serial No. 662,687.

To all whom it may concern:

Be it known that I, LOUIS SCHWITZER, a subject of the Emperor of Austria-Hungary, and a resident of Indianapolis, county of Marion, and State of Indiana, have invented a certain useful Starter for Internal-Combustion Engines; and I do hereby declare that the following is a full, clear, and exact description thereof, reference being had to the accompanying drawings.

The object of this invention is to provide an improved means for starting internal combustion engines and is particularly applicable to that class of automobile engines which make use of a rotary or reciprocatory sleeve valve.

The feature of the invention lies in the adaptation or use of suitable passageways in the movable sleeve or valve of an internal combustion engine, whereby compressed air, or other gas under pressure, may be admitted to that cylinder which has entered upon its power stroke, the piston forced outward, the crank shaft revolved and the engine caused to take up its regular cycle of events.

The nature of the invention will be understood from the accompanying drawings and the following description and claims:

In the drawings, Figure 1 is a vertical transverse section through one cylinder of an internal combustion engine making use of this invention, with portions broken away. Fig. 2 is a vertical longitudinal section on the line 2—2 of Fig. 1, with portions broken away and portions omitted, showing the gas connections. Fig. 3 shows a modified form of the invention.

In detail there is shown in the drawings an internal combustion engine having cylinders 10 with pistons 11 therein driving a crank shaft, not shown, through pitmen 12 and having a rotary valve upon the upper ends of the cylinders.

The construction of the rotary valve may be varied somewhat. As shown in the drawings, it lies parallel with the crank shaft upon the upper ends of the cylinders. Said valve is composed of two tubes, an inner tube 13 serving to convey the exhaust gases away from the cylinder and an outer tube 14 surrounding said inner member 13 and suitably spaced therefrom and the space between said inner and outer member forming a fuel passage for conducting the carbureted

mixture to the cylinders. As shown in the drawings, the valves are double ported and have diametrically opposed openings through the walls thereof which will mate with the ports 15 and 16 in a valve casing 17. These ports are spaced apart in such relation as to bring about the desired cycle of events in the engine. The valve may be caused to rotate by any desired means and at any desired speed.

It is well known that in multiple-cylinder internal combustion engines almost invariably the engine, when stopped, will come to rest with the pistons at about mid stroke and should a gas under pressure be admitted to that cylinder in which the piston has started upon its power stroke, the piston will be forced down, the crank shaft caused to rotate, and the regular cycle of events will be taken up by the engine. For this purpose a gas pipe 18 leading from any desired source of compressed gas, is tapped into the valve casing 17 at desired intervals and the fuel inlet valve is provided with grooves or depressions 19 in the outer surface thereof, one end of said grooves 19 connecting with a port 15 leading to the cylinder 10 and the other end of said groove 19 adapted to make contact with the inner end of the gas connection as the valve is rotated. Thus it will be seen that with the engine in the idle position, should compressed gas be turned into the pipe 18, it will pass by way of the grooves 19 and port 15 into that cylinder 10 in which the piston has started upon its power stroke, force said piston downward and cause the starting of the engine in the manner before described.

In all of those starters on the market so far as known, it is necessary that a complex valve mechanism be operated for each starting mechanism. With this invention, however, it will be necessary to have but one simple valve in the gas line for causing the stopping of the flow of gas from the source of supply to the valve casing.

A simple modification of this invention, and not departing whatever from the spirit of the invention, lies in substituting a plurality of double rotary valves for the one here shown. It is not desired, therefore, to limit myself to the specific construction shown.

By another modification of this invention

a separate passageway 21 is provided through the tubular valve which would connect the source of compressed gas with each cylinder when the pistons therein have entered upon their power stroke.

It is self evident that this invention can be applied with equal facility upon an engine making use of an oscillatory as well as upon a rotary valve construction. In the 10 preceding description and in the accompanying claims by the word "gas" is meant a single gas or a gaseous mixture such as air or other mixture or a union of two or more gases whether inert or active.

15 I claim as my invention:

1. In an internal combustion engine, the combination with a cylinder, a piston therein, a rotary fuel sleeve valve for said cylinder, an exhaust valve within said fuel valve, 20 ports in said valve for controlling the inlet to and the exhaust from said cylinder, and a casing for said fuel sleeve valve having a port in communication with the combustion chamber of said cylinder, of means for supplying gas under pressure to said fuel valve, 25 said fuel valve having a passageway located therein adapted as said sleeve valve is rotated to register with said gas supplying means and with said port to said cylinder, 30 whereby gas under pressure may be intro-

duced into said cylinder on the power stroke for actuating said piston and starting the engine.

2. In an internal combustion engine, the combination with a plurality of cylinders, a piston in each of said cylinders, a rotary fuel valve for said cylinders, an exhaust passage within said fuel valve, ports in said valves for controlling the inlet to and the exhaust from said cylinders, and a casing 35 for said fuel valve having a port in communication with each of said cylinders, of means for supplying gas under pressure to said fuel valve, said fuel valve having a plurality of longitudinal grooves in the 40 outer surface thereof, and adapted as the valve is rotated to register with said gas supplying means and with said cylinder ports, whereby gas under pressure may be introduced into said cylinders on the power 45 stroke, the piston therein forced outward and the engine started.

In witness whereof, I have hereunto affixed my signature in the presence of the witnesses herein named.

LOUIS SCHWITZER.
